DESIGN FOR A MOTOR HOUSING FOR VACUUM CLEANER

John R. Morgan, Oak Park, Ill., assignor to Sears, Roebuck and Co., Chicago, Ill., a corporation of New York

Application May 28, 1937, Serial No. 69,598

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Motor Housing for Vacuum Cleaner, of which the following is a specification, reference being had to the accompanying drawing, forming a part thereof.

Fig. 1 is a perspective view of a motor housing for vacuum cleaner embodying my new design.

Fig. 2 is a top plan view.

Fig. 3 is a front elevational view.

Fig. 4 is a side elevational view.

The side of the device not seen in the drawing is similar to the side which is shown.

I claim:

The ornamental design for a motor housing for vacuum cleaner, as shown and described.

JOHN R. MORGAN.
